CLAIM

The ornamental design for an upper portion of a beverage dispenser, as shown and described.

DESCRIPTION

FIG. 1 is a top perspective view of an upper portion of a beverage dispenser, showing our new design;

FIG. 2 is a bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The broken lines in the drawings depict portions of the upper portion of a beverage dispenser that form no part of the claimed design.
